FISHING REEL

Morris E. Wood, 128 Compton St., Bronson, Mich.

Filed July 20, 1959, Ser. No. 56,854

Term of patent 14 years

(Cl. D31—4)

Fig. 1

Fig. 2

The dominant features of my design reside in the full line portions of the drawing.

I claim:

The ornamental design for a fishing reel, as shown and described.
